LIGHTING SYSTEM

Willem F. Westendorp, Schenectady, N. Y., assignor to General Electric Company, a corporation of New York

Application November 18, 1933, Serial No. 698,618

8 Claims. (Cl. 176—124)

My invention relates to lighting systems and more particularly to lighting systems in which electric discharge lamps are used.

One object of my invention is to provide an improved method of operation of the lamps.

Another object of my invention is to provide an improved system for connecting the lamps in series with each other, in which the heating current for the cathodes of the lamps and the operating anode current are transmitted over the same circuit.

For a better understanding of my invention, together with other and further objects thereof, reference is had to the following description taken 15 in connection with the accompanying drawing, and its scope will be pointed out in the appended claims.

In the drawing, Fig. 1 illustrates diagrammatically a lighting system in accordance with my 20 invention; Figs. 2 and 3 show modifications thereof, and Fig. 4 illustrates the characteristics of the operating current used with the system shown in Fig. 3.

Referring to the drawing in detail, Fig. 1 illustrates diagrammatically a source of power 10 provided with a direct current terminal 11 and an alternating current terminal 12. A terminal 13 serves as a return for both currents. A primary winding 46 connected to any suitable supply of 25 alternating current energizes a secondary winding 47 which supplies alternating current through conductor 12. A secondary winding 48 connected at its midpoint to conductor 13 and at its ends to the anodes of vacuum tube rectifiers 30 49 whose cathodes are connected to each other through a resistance 50 supplies direct current 35 through conductor 11 which is connected to the midpoint of resistance 50. A time delay switch 14 is connected to energize, in succession, the operating coils 16 and 17 of switches 18 and 19. The switch 19 is provided with two contacts 21 and 22. When the switch is closed it engages contact 21 and thereby connects a conductor 23 to the direct current terminal 11. When the 40 switch 19 is in the open position, that is, when the coil 17 is deenergized, the switch engages contact 22 and thereby connects conductor 23 to the switch contact 24 of switch 18 through a conductor 25. When the operating coil 16 of switch 45 50 18 is energized, the switch closes and thereby connects the alternating current terminal 12 through contact 24, conductor 25, contact 22 and switch 19 to the conductor 23.

A number of discharge lamps 26, each provided 55 with an anode 27 and a filamentary cathode 28,

are supplied in series relation with current from conductor 23. Associated with each lamp 26 is a relay 30 having a coil 31, a core 32, a short-circuited coil mounted on the end of the core and a movable contact arm 34. The short circuited 5 coil mounted on the end of the core may be a coil of low resistance wire having several turns. The simplest possible structure is preferable, however, and in the drawing a plain copper disk 33 is illustrated as being mounted on the end of 10 the core 32. When the coil 31 is energized by alternating current, the flux in the core generates eddy currents in the disk 33 which then acts as a single turn short-circuited coil, and the accompanying flux neutralizes the flux of coil 31 which 15 tends to lift the contact arm 34. Due to the short-circuited coil 33, therefore, the relay is insensitive to alternating current and therefore when the conductor 23 is connected to the alternating current source through switch 18 the contact arms 34 remain in the open position. In the open position contact arms 34 engage contacts 36 respectively, which are connected respectively through conductor 37 to one end of a filamentary cathode 28. The other end of each cathode is 20 connected through a conductor 38 to the coil 31 of a second relay 30. In this arrangement the cathode of the last discharge lamp 26 is connected to the common return terminal 13 through a conductor 40. Each of the lamps 26 is further 30 shunted by conductors 41 and 42 connected respectively to the anode and cathode of the tube and through suitable contacts to opposite sides of a film cutout device 43, which breaks down and permits current to flow only when the tube fails 35 during operation.

In operation the time delay relay 14 first energizes, in accordance with its setting, the coil 16 of switch 18. Since at this time the switch 19 is in the open position a circuit is closed by switch 40 18 from the alternating current terminal 12 through the switch 18, contact 24, conductor 25, contact 22, switch 19 and conductor 23 to the first relay coil 31. Since, as stated above, this relay is insensitive to alternating current, the 45 contact arm 34 remains unaffected and maintains a circuit through its contact 36 and conductor 37 to the first filamentary cathode 28. The other end of this cathode is connected through a conductor 38 to the second coil 31 50 through which the current flows to the secondary filamentary cathode 28. Current thereby flows in a similar manner through each of the filamentary cathodes in series and through conductor 40 to the return terminal 13, thereby heating the 55

cathodes. When the cathode surfaces have reached the proper temperature, which is reached after a predetermined period of time during which the heater current is flowing, the time 5 switch 14 energizes the coil 17 of switch 19. The contact arm of switch 19 is thereby moved into engagement with contact 21 and connects conductor 23 to the direct current terminal 11 of the source 10. With this connection, direct current 10 flows into coil 31, causing the contact arm 34 to raise and disengage the contact 36. Due to the preheating of the cathode, however, the discharge path within the tubes 26 has become conductive due to the electron emission from the cathode and 15 current thereby flows through the tubes, the circuit being from coil 31 through a conductor 45 to the first lamp 26, anode 27, across the discharge path within the lamp, cathode 28, through conductor 38 to the next coil 31 and so on to conductor 40 and to the common return terminal 13. In this arrangement, therefore, the filamentary cathodes of the discharge lamps are connected in series with each other when alternating current is supplied to the circuit and the lamps or discharge paths thereof are connected in series with 20 each other when direct current is supplied to the circuit.

In the above system discharge lamps having a filling of sodium vapor therein, together with such 30 gases as neon and argon, are preferably used. It is desirable to maintain the necessary electron emission from the cathodes during operation and therefore heat must be supplied to the cathodes. In the above-described arrangement, this heating 35 during operation of the lamp is accomplished by the arc discharge within the lamp.

In Fig. 2 I have shown a modification of the cathode 28 in which the anode current flows through the filament which is arranged in series 40 relation to the discharge path. In this modification the cathode comprises a conductive metal tube 47 within which a filament 48 is totally enclosed and connected to the tube at one end. With this type of cathode the filament can be 45 connected in series with the discharge path so that the operating or anode current can be used to heat the tube 47. Fig. 2, illustrates an arrangement in which the cathode tube 47 is connected by a conductor 50 to the contact 36, relay 50 arm 34 and to the relay coil 31. When alternating current is applied the filaments are connected in series with each other as in Fig. 1 but when direct current is applied the relays break the shunt circuit about each lamp and the discharge 55 current flows from each anode 27 to the cathode envelope 47 through the filament 48 to the next anode.

In Fig. 3 I have illustrated another modification of my invention in which the filamentary cathode 28 is connected to the secondary winding 52 of a transformer 53. The midpoint of the winding 52 is connected to one end of the primary winding 54 of the transformer 53. The transformer 53 is provided with an open core for the 60 purpose of preventing saturation thereof. With this arrangement alternating current is supplied to the primary windings 54, which are connected in series by relays 30, in the same manner as the filaments 28 are connected in series in the system disclosed in Fig. 1. The windings 54 are disconnected from each other by the relays 30 as soon as direct current is applied to the circuit and the discharge current flows from the filament 28 to 65 the winding 52, then through the connections 55

to one end of winding 54 and through the winding to the next anode.

In the arrangement of Fig. 3 a direct current having superposed thereon a ripple current, as diagrammatically illustrated in Fig. 4, for example, is supplied to the system after the alternating current has been flowing through the filament a predetermined time. The discharge paths having been made conductive through pre-heating, as in the arrangement shown in Fig. 1, 10 in combination with the action of transformer 53, the direct current will flow through the tubes in series with each other. The anode current will also flow through the cathode and through the primary windings 54 in series with each other. 15 The ripple current superposed upon the direct current will thereby excite the transformer winding 52 and cause an independent current flow in the secondary winding 52 and cathode 28. In the rectifier circuits, which are normally 20 used, a 120 cycle ripple voltage is generated, which when impressed upon the arrangement shown in Fig. 3 is sufficient to energize the filaments to the proper temperature for maintaining a predetermined electron discharge from its surface.

In accordance with the provision of the patent statutes, I have described the principle of operation of my invention, together with the apparatus which I now consider to represent the best embodiment thereof; but I desire to have it understood that the apparatus shown is only illustrative, and that the invention may be carried out by other means.

What I claim as new and desire to secure by Letters Patent of the United States is:

1. In a series lighting system, the combination of a direct current source and an alternating current source, a plurality of electric discharge lamps, each provided with an incandescent cathode and an anode, means for connecting the cathodes of said lamps in series with each other and to said alternating current source, and means for connecting said devices in series relation to said direct current source and for simultaneously breaking the connections between said cathodes.

2. In a series lighting system, the combination of a direct current source and an alternating current source, a plurality of electric discharge lamps, each provided with a filamentary cathode and an anode connected in series with each other, means for connecting said lamps to said alternating current source and for simultaneously establishing a shunt circuit about each lamp whereby the cathodes only of said lamps are connected in series with each other, and time controlled means for simultaneously connecting said lamps to said direct current source and for breaking the shunt circuits about each lamp.

3. In combination, an electric discharge device including an envelope containing an ionizable gas provided with a filamentary cathode and an anode, a circuit between said anode and one end of said cathode and a relay operable only by direct current flowing through said device and arranged to normally close said circuit from one end of said cathode to the anode and to break said circuit when direct current is applied across said anode and cathode.

4. In combination, an electric discharge device provided with a filamentary cathode and an anode, a transformer provided with a winding connected in series with said device and provided with a second winding connected to said cathode, and means for providing a direct current having

an alternating current component for creating a discharge across said electrodes and for heating said cathode.

5. The method of operating an electric discharge device having an anode and a filamentary cathode which consists in applying a rectified current having an alternating current component for operating the discharge tube and for applying said alternating current to the cathode of said tube for the purpose of heating it.
10. In a series lighting system, the combination of a direct current source, and alternating current source, a plurality of electric discharge lamps, each provided with a cathode, an anode and circuit connections between said lamps for connecting them in series relation to each other, means for connecting said lamps to said alternating current source, means for conducting current from said source to said cathodes in series relation and in shunt to the respective discharge paths between said anodes and cathodes, means for connecting said lamps to said direct current source a predetermined time after the first connection is made, and means for conducting the current from said second source across the electrodes within said lamps respectively.
15. In a series lighting system, the combination of a direct current source, and alternating current source, a plurality of electric discharge lamps, each provided with a cathode, an anode and circuit connections between said lamps for connecting them in series relation to each other, means for connecting said lamps to said alternating current source, means for conducting current from said source to said cathodes in series relation and in shunt to the respective discharge paths between said anodes and cathodes, means for connecting said lamps to said direct current source a predetermined time after the first connection is made, and means for conducting the current from said second source across the electrodes within said lamps respectively.
20. In a series lighting system, the combination of a direct current source, and alternating current source, a plurality of electric discharge lamps, each provided with a cathode, an anode and circuit connections between said lamps for connecting them in series relation to each other, means for connecting said lamps to said alternating current source, means for conducting current from said source to said cathodes in series relation and in shunt to the respective discharge paths between said anodes and cathodes, means for connecting said lamps to said direct current source a predetermined time after the first connection is made, and means for conducting the current from said second source across the electrodes within said lamps respectively.
25. In a series lighting system, the combination of a direct current source, and alternating current source, a plurality of electric discharge lamps, each provided with a cathode, an anode and circuit connections between said lamps for connecting them in series relation to each other, means for connecting said lamps to said alternating current source, means for conducting current from said source to said cathodes in series relation and in shunt to the respective discharge paths between said anodes and cathodes, means for connecting said lamps to said direct current source a predetermined time after the first connection is made, and means for conducting the current from said second source across the electrodes within said lamps respectively.

7. In a lighting system, the combination of an electric discharge lamp provided with an anode, a cathode, a heater for said cathode, an envelope containing an ionizable gas for enclosing said electrodes, a circuit normally connecting said anode to one end of said heater and in shunt to said electrodes, means for supplying alternating current to said lamp electrodes for energizing said heater and means responsive to direct current flowing to said electrodes for breaking said shunt circuit and thereby establishing a discharge across said electrodes.

8. In a series lighting system, the combination of a plurality of electric discharge lamps, each provided with an incandescent cathode, an anode, and an envelope containing a vaporizable metal for enclosing said electrodes, a circuit normally connecting said cathodes in series with each other, and means responsive to direct current flowing in said circuit for breaking said circuit and for simultaneously connecting said lamps in series with each other.

WILLEM F. WESTENDORP. 25
